Primary Examiner—Jeffrey Asch**[57] CLAIM**

The ornamental design for a slotted gas cap remover with large diameter top, as shown and described.

DESCRIPTION

FIG. 1 is a front elevation view of a slotted gas cap remover with large diameter top, the rear being the same in appearance, and each side being the same in appearance without the slot; and,

FIG. 2 is a bottom plan view, the top view has the appearance of a plain, solid circle, and the center most concentric circle in this view indicates that the center is a hollow tube which continues completely through the article to the solid top surface.
